UNITED STATES PATENT OFFICE.

WILLIAM J. H. STRONG, OF CHICAGO, ILLINOIS.

DESIGN FOR A BASE FOR MOTOR-STANDS.

54,566.

Specification for Design.

Patented Mar. 2, 1920.

Application filed May 6, 1918. Serial No. 232,955. Term of patent 3½ years.

To all whom it may concern:

Be it known that I, WILLIAM J. H. STRONG, citizen of the United States, residing at Chicago, in the county of Cook and State of Illinois, have invented a new, original, and ornamental Design for a Base for Motor-Stands, of which the following is a specification.

The figure is a side elevation of a group of three of the legs assembled together to form a base for a motor, each leg shows my new design.

I claim:

The ornamental design for a base for motor stands, as shown.

WILLIAM J. H. STRONG.
